UNITED STATES PATENT OFFICE.

WILLIAM T. PRINGLE, OF WYNCOTE, PENNSYLVANIA.

ELECTRIC SWITCH.

1,252,838.

Specification of Letters Patent.

Patented Jan. 8, 1918.

Application filed January 20, 1915. Serial No. 3,264.

To all whom it may concern:

Be it known that I, WILLIAM T. PRINGLE, a citizen of the United States, residing at Wyncote, in the county of Montgomery and 5 State of Pennsylvania, have invented a certain new and useful Improvement in Electric Switches, whereof the following is a specification, reference being had to the accompanying drawing.

10 My invention is applicable to knife switches and may be employed with particular advantage in connection with such switches wherein the blades are devoid of operating handles. Switches of such simple 15 type are employed in circuits carrying heavy current, where they normally remain closed but are provided so that the circuit may be broken by opening them in case of emergency. However, it is to be understood 20 that my invention may be employed in switches of any desired form.

It is now known that, aside from the mechanical strains, tending to open them, to which such switches are normally subjected; 25 under abnormal conditions, such as an overload of the circuit in which they are included, such switches are subjected to electrical stresses tending to separate the blades from their terminals, so that under such abnormal electrical conditions the switch 30 blades may be automatically thrown open, unless means be provided to positively prevent such abnormal movement. Therefore, it is the object of my invention to provide 35 means for positively locking a blade of a knife switch in closed position, so constructed and arranged that it cannot be released by any electrical strain to which the switch may be subjected, and cannot be released 40 by any accidental mechanical strain, but requires for its release a predetermined movement of the locking means such as may only be imparted to it intentionally.

As hereinafter described my invention includes the combination with a switch blade and the terminal with which it is adapted to detachably electrically connect, of a locking spring forming an abutment which normally obstructs the passage of the blade to 45 open position and prevents its opening movement until said spring is moved aside. In the form of my invention hereinafter described the spring extends transversely to the length of the blade and is so slotted that 50 the end of the blade projects through the spring when the blade is in closed position;

so that the spring must be shifted longitudinally with respect to the blade to free the end of the latter.

My invention includes the various novel 60 features of construction and arrangement hereinafter more definitely specified.

In the drawings; Figure I is a front view of a switch comprising a single blade and embodying my invention.

Fig. II is a side elevation of the switch shown in Fig. I.

Fig. III is a fragmentary side elevation of the switch operating handle indicated in broken lines in Fig. II.

In said figures; 1 is an insulating base which may be of any suitable form or material, for instance a plane slate slab, which supports the switch terminals 2 and 3 which are conveniently connected therewith by 75 their respective screw threaded shanks 5 and 6 extending through said slab, in engagement with respective electrical conductors of the circuit in which the switch is included. Said shanks are conveniently engaged by the nuts 8 and 9 to hold said terminals 2 and 3 in rigid relation with said slab.

The switch blade 10 is pivoted to said terminal 2, conveniently by the bolt 11, so 85 that it may be turned to and from contact with the switch terminal 3, and when closed in contact with the latter may occupy the position shown in Fig. II, in which position said blade 10 is normally retained by the 90 locking spring 14 which is held stationary at one end between said slab 1 and terminal 3 and has the slot 15 through which the end of said switch blade 10 projects, so that said spring extends transversely to the length of 95 said blade, and its unslotted free end 16 forms an abutment which must be displaced in the direction of the length of said blade to release the latter so that it may be opened. Such releasing movement may be 100 effected in any convenient manner, but I find it convenient to employ an operating handle 17 having the pin 18 for engagement in the hole 19 in the end of said switch blade 10, and having the cam flange 20 adapted 105 to bear upon the locking spring 14 to shift the latter clear of the blade when said handle is turned from the position shown in dash lines in Fig. II to the position shown in dot and dash lines in said figure. 110 When turned to the latter position; said handle may be employed to swing the switch

blade 10 open, by the continued engagement of its pin 18 in said hole 19. Of course, said spring 14 returns, of its own resiliency, to the position shown in the drawings, when released from engagement with the handle flange 20, by the opening movement of the blade 10, above described.

Although it is not necessary to do so, I prefer to so incline the end of the switch 10 blade 10, for instance as shown at 21, that stresses upon said blade tending to open it press said inclined portion of the blade against the abutment end 16 of said spring in such manner as to offer additional resistance to the releasing movement of the 15 spring.

Said blade 10 may be returned to the closed position shown, without any manipulation of said spring 14; the inner corner of 20 the free end of said blade 10 being rounded as indicated at 23 so as to slide past the oppositely rounded abutment end 16 of the locking spring 14 and automatically reengage the latter.

25 Although, in applying my invention to the simple type of switch chosen for illustration, I find it convenient to so construct and arrange the locking spring as to engage the end of the switch blade; it is to be understood that other forms and arrangements 30 of my invention may be employed.

Therefore, I do not desire to limit myself to the precise details of construction and arrangement herein set forth, as it is obvious that various modifications may be made therein without departing from the essential features of my invention as defined in the appended claims.

I claim:—

40 1. In an electric switch, the combination with an insulating base; of two switch terminals mounted on said base; a switch blade pivotally connected with one of said terminals and arranged to swing to and from 45 electrical contact with the other of said terminals; a locking spring having one end held between the last named terminal and said base and having its free end extending transversely to the length of said blade, with 50 a slot through which the free end of said blade projects when in closed position; said locking spring having its unsloped free end rounded and arranged as an abutment which 55 normally obstructs the passage of said blade in open position and prevents its opening 60 movement until said spring is moved aside; said blade having its portion which engages said abutment so inclined that stresses upon said blade tending to open it press said inclined portion thereof against the abutment 65 in such manner as to offer additional resistance to the releasing movement of the spring, and the inner corner of the free end of said blade being rounded and arranged to coöperate with the rounded end of said spring to

move the latter aside when said blade is shifted from open to closed position, and said blade having a hole adjacent said spring, arranged to engage an operating handle; and, an operating handle having a 70 pin adapted to turn in the hole of said blade, and having a cam flange arranged to encounter said spring and release it from said blade by shifting said spring longitudinally with respect to said blade when said 75 handle is turned.

2. In an electric switch, the combination with an insulating base; of two switch terminals mounted on said base; a switch blade pivotally connected with one of said terminals and arranged to swing to and from 80 electrical contact with the other of said terminals; a locking spring extending transversely to the length of said blade, with a slot through which the free end of said blade 85 projects when in closed position; said locking spring having its unsloped free end arranged as an abutment which normally obstructs the passage of said blade to open position and prevents its opening movement 90 until said spring is moved aside; said blade having its portion which engages said abutment so shaped that stresses upon said blade tending to open it press said inclined portion thereof against the abutment in such 95 manner as to offer additional resistance to the releasing movement of the spring, and the inner corner of the free end of said blade being shaped to coöperate with said spring to move the latter aside when said blade is 100 shifted from open to closed position, and said blade having a hole adjacent said spring, arranged to engage an operating handle; and, an operating handle having a 105 pin adapted to turn in the hole of said blade, and having means arranged to encounter said spring and release it from said blade when said handle is turned.

3. In an electric switch, the combination with an insulating base; of two switch terminals mounted on said base; a switch blade pivotally connected with one of said terminals and arranged to swing to and from 110 electrical contact with the other of said terminals; a locking spring arranged as an abutment which normally prevents its opening movement until said spring is moved aside; said blade having its portion which engages said abutment so inclined that 115 stresses upon said blade tending to open it press said inclined portion thereof against the abutment in such manner as to offer additional resistance to the releasing movement of the spring, and the inner corner of the free end of said blade being shaped to coöperate with said spring to move the latter aside when said blade is shifted from 120 open to closed position; and said blade having means adjacent said spring, arranged to engage an operating handle; and, an oper- 125

ating handle having means arranged to engage said blade and means arranged to encounter said spring and release it from said blade.

5 4. In an electric switch, the combination with an insulating base; of two switch terminals mounted on said base; a switch blade pivotally connected with one of said terminals and arranged to swing to and from electrical contact with the other of said terminals; a locking spring arranged as an abutment which normally prevents its opening movement until said spring is moved aside; said blade having its portion which engages 10 said abutment so inclined that stresses upon said blade tending to open it press said inclined portion thereof against the abutment in such manner as to offer additional resistance to the releasing movement of the 15 spring, and the inner corner of the free end of said blade being shaped to coöperate with said spring to move the latter aside when said blade is shifted from open to closed position; and, an operating handle having 20 means arranged to engage said blade and means arranged to encounter said spring and release it from said blade.

5. In an electric switch, the combination with an insulating base; of two switch terminals mounted on said base; a switch blade pivotally connected with one of said terminals and arranged to swing to and from electrical contact with the other of said terminals; a locking spring arranged as an 25 abutment which normally prevents its opening movement until said spring is moved aside; said blade being shaped to coöperate with said spring to move the latter aside when said blade is shifted from open to closed position; and, an operating handle having means arranged to engage said blade and means arranged to encounter said spring and release it from said blade.

6. In an electric switch, the combination with an insulating base; of two switch terminals mounted on said base; a switch blade pivotally connected with one of said terminals and arranged to swing to and from electrical contact with the other of said 30 terminals; a locking spring arranged as an abutment which normally prevents opening movement of said blade; said blade having its portion which engages said abutment so shaped that stresses upon said blade tending to open it press said portion thereof against

the abutment in such manner as to offer additional resistance to the releasing movement of the spring, and the inner corner of the free end of said blade being shaped to coöperate with said spring to move the latter 35 aside when said blade is shifted from open to closed position, and said blade having a hole adjacent said spring, arranged to engage an operating handle; and, an operating handle having a pin adapted to turn in the 40 hole of said blade, and having means arranged to encounter said spring and release it from said blade when said handle is turned.

7. In an electric switch, the combination with an insulating base; of two switch terminals mounted on said base; a switch blade pivotally connected with one of said terminals and arranged to swing to and from electrical contact with the other of said 45 terminals; a locking spring arranged as an abutment which normally prevents opening movement of said blade; said blade having a portion which directly engages said spring so shaped that stresses upon said blade tending to open it press said portion thereof against the spring in such manner as to offer additional resistance to the releasing movement of the spring, and the inner corner of the free end of said blade being 50 shaped to coöperate with said spring to move the latter aside when said blade is shifted from open to closed position.

8. In an electric switch, the combination with an insulating base; of two switch 55 terminals mounted on said base; a switch blade pivotally connected with one of said terminals and arranged to swing to and from electrical contact with the other of said terminals; a locking spring arranged as an 60 abutment which normally prevents opening movement of said blade; said blade having a portion which engages said spring so shaped that stresses upon said blade tending to open it press said portion thereof against the 65 spring in such manner as to offer additional resistance to the releasing movement of the spring.

In testimony whereof, I have hereunto signed my name at Philadelphia, Pennsylvania, this fifth day of January, 1915.

WILLIAM T. PRINGLE.
